UNITED STATES PATENT OFFICE.

ELZIE E. JONES, OF MISSOURI VALLEY, IOWA.

ICE-CUTTING MACHINE.

SPECIFICATION forming part of Letters Patent No. 629,964, dated August 1, 1899.

Application filed April 28, 1899. Serial No. 714,852. (No model.)

To all whom it may concern:

Be it known that I, ELZIE E. JONES, a citizen of the United States, residing at Missouri Valley, in the county of Harrison and State of Iowa, have invented a new and useful Ice-Cutting Machine, of which the following is a specification.

This invention relates to ice-cutting machines; and the object of the invention is to provide a simple and efficient apparatus of this character which can be readily and quickly shifted from place to place along the ice and which can cut the latter in predetermined sizes, and the apparatus includes also hand-operated means for propelling the same.

With these ends in view the invention consists in the novel combination of elements and in the construction and arrangement of parts, which will be hereinafter fully described and claimed.

To enable others to understand the invention, I have illustrated the preferred embodiment thereof in the accompanying drawings, forming a part of this specification, and in which—

Figure 1 is a side elevation of an ice-cutting machine constructed in accordance with my invention. Fig. 2 is a top plan view of the machine. Fig. 3 is a front elevation of the machine. Fig. 4 is a rear elevation, partly in section. Fig. 5 is an enlarged detail sectional view of the traction mechanism. Fig. 6 is a detail in perspective of the gage or guide. Fig. 7 is a detail in perspective of the supporting-bracket for the gage or guide.

Like characters denote like and corresponding parts in each of the several figures of the drawings.

The different parts of the machine are supported upon a platform, which may be of any suitable construction or material adapted to sustain said parts and one or more operators for turning the hand-crank to drive the propelling mechanism, and the platform is denoted by P, and it is provided at suitable intervals with the depending runners 2, secured to its opposite edges and adapted to travel upon the ice when the machine is shifted along the same when in use.

The uprights or standards 3 are secured to the upper side of the platform and extend

vertically therefrom, and the braces 4 are secured to the standards and project diagonally and oppositely therefrom, one end of the braces being secured to the platform or deck, while the other end sustains the main driving-shaft 5, which is manually operated, preferably, by the workmen, who stand at opposite sides of the two standards. The shaft 5 is provided with a master gear-wheel 6 and also at its opposite ends with the cranks 7, provided with handles which are grasped by the two workmen who stand upon the platform. The master gear-wheel is connected by a train of intermeshing gears with the saw, which is of the rotary circular kind and which is carried by a tilting frame.

The saw is denoted by S, and it is adapted to be lowered in contact with the ice for the purpose of cutting a groove therein and the depth of which can be regulated by raising or lowering the saw-frame F. The saw-shaft is denoted by 8, and it is carried at the extreme outer end of the frame and is provided with a pinion 9, meshing with the gear 10, which in turn meshes with a gear 12 and the shafts of which are supported by the side bars 13 of the saw-frame. The gear 12 meshes with the wide pinion 14, which receives rotary motion from the gear 15, carried by the shaft 16, which in turn is provided with a pinion 17, meshing with the master-gear 6. The pinion 14 is carried by the shaft 18, which, with the shaft 16, is rotatively supported by the angularly-disposed braces 4, and the shaft 18 is in the nature of a pivot for sustaining the tilting saw-frame F and permitting the necessary adjustments thereof, the side members of the frame having openings to receive said shaft. Upon an inspection of the drawings it will be seen that the train of meshing gears is a multiplying one, whereby the saw will be driven at a high rate of speed for the purpose of cutting the ice.

The platform has a longitudinal slot 19 near its forward end, through which the circular saw S can be passed when its frame F is lowered for the purpose of reaching the ice, and the depth of the groove can be regulated and the saw held firmly in its adjusted position.

A sector is shown at 20 having a flange 21, which is adapted to receive fastening devices to hold said sector in place, and the hand-

lever 22 is fulcrumed to the sector and carries a gravity-pawl 23, adapted to engage the teeth of the sector. The link 24 is jointed to the hand-lever above its fulcrum and is likewise connected with the crank-arm 25 on the shaft 26, which is supported by the vertical skeleton brackets or risers 27 near the front of the platform, and said crank-shaft is provided with a second crank-arm 28 at its opposite end, which is pivoted to the bail 29, the branches of which have eyes to receive the transverse shaft 30, located between the side pieces 13 of the side frame. When the pawl 23 is lifted out of engagement with the teeth of the sector 20, the saw-frame can be lowered the proper distance by swinging the hand-lever 22 forward, and the reverse operation can be secured by oppositely moving the hand-lever, and the frame may be maintained in the selected position by permitting the pawl to fall in engagement with the co-operating teeth of the sector.

The longitudinal rod 31 is jointed to the gravity-pawl 23 and also to the small elbow-lever 32, pivoted to the hand-lever near the handle thereof, and by operating the small lever the pawl can be raised clear of the sector-teeth through the intermediate connecting-rod.

It will be remembered that the machine is moved from place to place along the ice by means of manually-operated driving or propelling mechanism, the operators standing upon the platform near the rear of the machine.

Two traction-wheels are represented at 33, and they are carried by the shaft 34, which is rotatively supported by the yieldingly-mounted frame 35, the side bars of which are adapted to receive the shaft 35', supported by the brackets or bearings 36 upon the uprights 3, and this shaft is provided with a cone speed-sprocket 37, any one of the different-sized wheels of which sprocket is adapted to receive the sprocket-chain 8, which passes over the complementary wheel of the reversely-arranged cone speed-sprocket 39, secured to the main shaft 5. The cones represented obviate removal and a different-sized one can be substituted for the purpose of effecting changes in the speed of the machine. The shaft 35' is provided with a pinion 40, meshing with the gear 41, the shaft of which is carried by the yieldingly-mounted frame 35 and which meshes with the pinion 42 upon the traction-wheel shaft or axle 34, and by rotating the power-shaft the traction-wheels may be rotated for the purpose of driving the machine either forward or backward, as occasion requires.

The frame 35 is held down with the traction-wheels thereon in contact with the ice by means of the spring 43, having a loop 44 at one end fitting over the squared portion 45 of the fixed shaft 46, supported by bearings 47 upon the platform or deck P, and the opposite end of the spring has an eye to receive the bail 48, the branches of which are con-

nected to the side pieces of said yieldingly-supported frame. The gear-wheels are preferably mounted upon roller-bearings, and their shafts are fixed or stationary. The traction-wheel frame projects through a slot or opening 49 in the platform, and it is lifted clear of the ice by means of the lever 50, secured to the rock-shaft 46, and said lever is adapted to engage projections or teeth upon the adjacent standard or upright 3 for the purpose of holding it in its shifted position and therefore maintaining the frame elevated.

Means are provided for lifting the rear runners off the ice when it is necessary to turn the machine, and said means includes in its construction the feed-screw 51, which extends loosely through the angular shoe 52, located below the platform and the working portion of which is normally disposed above the runners 2. When, however, it becomes necessary to elevate the rear end of the machine, the feed-screw is turned, thereby forcing the shoe against the ice and elevating the platform as the feed operation progresses and of course lifting the runners at the rear off the ice. The screw 51 is vertically disposed and passes through the fixed nut 53, secured to the under side of the platform, and is provided with a hand-wheel 54, by which it may be turned, and is supported near its upper end by the riser 55. The hand-wheel is provided with a handle 56, by which it can be readily turned.

The machine is equipped with a gage device by which the distance between the cuts or grooves can be regulated with precision, and this gage device is adjustable and preferably laterally of the platform and serves to hold the saw at the proper distance from the cut, thereby insuring uniformity.

The gage device consists of a plate 57, which is vertically disposed and which is in parallelism with the saw; but this parallelism can be varied, of course, to separate the two parts at different distances, and the plate is made sufficiently long to prevent side motion of the machine when it is in a cut. The shank of the gage-plate is denoted by 58, and it is of U shape, and its cross-bar is adapted to be held in two alined notches 59, formed in the vertical duplicate walls of the bracket 60, which is secured to the upper side of the platform in proximity to the saw, and it will be understood that each of the walls or flanges of the bracket has a series of notches into which the transverse portion of the U-shaped shank of the gage device can be set, and the shank, and consequently the gage device, will be held in fixed position by means of the L-shaped spring 61, which bears against said transverse portion of the shank.

In operation the saw will be lowered to the proper extent and will be held in such position in the manner hereinbefore specified, after which the machine will be driven forward by rotating the power-shaft 5 through the intermediate connections, and simultane-

ously the saw will be rotated to cut a groove or channel in the ice, and in making the second cut the gage device will be inserted in the first cut, so as to insure the travel of the 5 machine in the proper path.

Changes in the form, proportion, size, and the minor details of construction within the scope of the appended claims may be resorted to without departing from the spirit or sacrificing any of the advantages of this invention.

Having thus described the invention, what I claim is—

1. In a machine of the class specified, the combination with a platform and with means 15 for propelling the same, of a saw, a tilting frame, a power-shaft provided with hand-crank, driving mechanism between the power-shaft and the saw, traction-wheels operatively connected with and driven by said 20 power-shaft, a frame for supporting the traction-wheels, a shaft, a bail connected with the frame, and a spring secured respectively to the shaft and to the bail, substantially as described.

2. In a machine of the class specified, the combination with a platform and with means 25 for propelling the same, of a saw, a tilting frame for carrying the saw, means for lifting said frame, a power-shaft, driving mechanism 30 between the power-shaft and the saw, traction-wheels operatively connected with and driven by said power-shaft, a rock-shaft having a squared portion, a spring provided with a loop fitting over said squared portion, a frame for 35 carrying the traction-wheels, a bail secured respectively to the frame and to said spring, and a lever fixed to said rock-shaft, substantially as described.

3. In a machine of the class specified, the 40 combination with a platform, of a tilting frame provided with a saw, means for raising and lowering the frame, a power-shaft operatively connected with the saw, a gage-plate provided with a shank, and a notched bracket secured 45 to the platform, the notches being adapted to receive the shank, substantially as described.

4. In a machine of the class described, the combination with a platform, of a tilting frame provided with a saw, means for raising and 50 lowering the frame, a power-shaft operatively connected with the saw, a gage-plate provided with a shank, a notched bracket secured to the platform, the notches being adapted to receive the shank, and a spring bearing 55 against said shank, substantially as described.

5. In a machine of the class specified, the combination with a platform and with means 60 for propelling the same, of a saw, a tilting frame for carrying the saw, means for lifting said frame, a gage-plate disposed in parallelism with the saw and provided with a U-shaped shank, a bracket provided with upright walls having alined notches to receive the cross portions of said shank, and a spring 65 secured to the platform and bearing against said crossed portion, substantially as described.

6. In a machine of the class specified, the combination of a platform and with means for propelling the same, of a saw, a tilting frame 70 for carrying the saw, means for lifting the frame, a series of runners depending from the platform, a feed-screw carried by the platform and provided with a hand-wheel and carrying at its lower end a shoe which is normally disposed above the lower edges of said runners, 75 traction-wheels, a pivoted frame for the traction-wheels, a rock-shaft having a squared portion, a spring provided with a loop fitted over said squared portion, a bail secured to 80 the traction-wheel frame and to said spring, and means for operating the rock-shaft, substantially as described.

7. In a machine of the class specified, the combination of a platform and with means for propelling the same, of a saw, a tilting frame 85 for carrying the saw, means for lifting the frame, a series of runners depending from the platform, a feed-screw carried by the platform and provided with a hand-wheel and carrying 90 at its lower end a shoe which is normally disposed above the lower edges of said runners, and a gage device disposed in parallelism with the saw and transversely adjustable relatively to the platform, traction-wheels, a pivoted 95 frame for the traction-wheels, a rock-shaft having a squared portion, a spring provided with a loop fitted over said squared portion, a bail secured to the traction-wheel frame and to said spring, and means for operating the 100 rock-shaft, substantially as described.

8. In a machine of the class specified, the combination with a platform having a series 105 of depending runners, of a power-shaft, a tilting frame provided with a saw, a series of intermeshing speed-multiplying gears intermediate the power-shaft and the saw, a sector, a lever connected with said frame and provided with a pawl adapted to coöperate with the teeth of the sector, traction-wheels, a yielding-supported frame for carrying the traction-wheels, means for raising and lowering 110 said last-mentioned frame, a feed-screw carried by the platform and provided with a hand-wheel and with a shoe, operative connections between said power-shaft and the traction-wheels, and a gage-plate parallel with 115 the saw and adjustably connected with the platform, substantially as described.

9. In an ice-cutting machine, the combination with the platform, of a vertically-adjustable swinging frame carrying a saw, a correspondingly-adjustable swinging frame carrying traction-wheels, a rock-shaft having a squared portion, a spring provided with a loop 120 fitted over said squared portion, a bail secured to the traction-wheel frame and to said spring, means for operating the rock-shaft and common power-gearing for simultaneously transferring motion to the saw and said traction-wheels, substantially as set forth.

10. In an ice-cutting machine, the combination with the platform and a cutting-saw supported thereon, of a vertically-swinging frame

carrying traction mechanism, and an adjustable spring operatively connected with said frame to provide for holding the traction device on the ice, substantially as set forth.

5 11. In an ice-cutting machine, the combination with the platform and a cutting-saw supported thereon, of a vertically-swinging frame carrying traction mechanism, and a rock-shaft carrying an offstanding spring operatively connected with said frame, substantially as set forth.

10 12. In an ice-cutting machine, the combina-

tion of the platform carrying propelling and cutting mechanism, of a gage-plate having an offstanding bail pivotally and adjustably connected with the platform, substantially as set forth. 15

In testimony that I claim the foregoing as my own I have hereto affixed my signature in the presence of two witnesses.

ELZIE E. JONES.
